UNITED STATES PATENT OFFICE

JOHN POPOFF, OF NEW YORK, N. Y.

SKY WRITING APPARATUS

Application filed August 5, 1930, Serial No. 473,171. Renewed June 15, 1932.

This invention relates to sky writing and my improvements are directed to means whereby groups of orifices in a series thereof, each orifice provided with a magnetically controlled valve, can be employed for the issuance of smoke in the production, against the sky, of letters or other desired characters, whereby words or devices may be visible from below.

10 Heretofore, in the art of sky writing it has been necessary to so manoeuvre an airplane that an issuing stream of smoke will become shaped into letters and words, this method having the disadvantage, in addition to the 15 exercise of skill required of the pilot, that the letters first written are apt to become dissipated before completion of a word.

Therefore, it is one of the purposes of my invention to provide an apparatus, which 20 may be in the form of an airplane, having a series of outwardly directed orifices, whereof different groups may be used selectively for the issuance of smoke in different shapes, thereby creating, for example, smoke letters, 25 characters or designs, and displaying them against the sky.

If a monoplane is employed the upper surface of its main wing is pierced with rows of orifices, each controlled by a valve that is 30 normally closed, but can be opened through the agency of an electro-magnet. The wing being hollow, or having a compartment therein, is adapted to receive the engine exhaust, with which may be mixed some enriching substance adapted to render the exhaust more smoke like in appearance.

Carried upon the airplane is a machine 40 that is provided with a key board which may resemble that of a typewriter. Each character key of the key board, when depressed, may serve to close an electrical circuit with a generator that is also carried by the airplane, the depression of said key, in addition, having the effect of energizing a motor, 45 which operates a rotating member that then makes successive contacts with circuit leads for the operation of the valves that control orifices comprised in the group for producing the smoke character indicated by the depressed key.

Other features and advantages of my invention will hereinafter appear.

In the drawings:

Figure 1 is a partial side elevation of an airplane having a generator and showing 55 means for conveying the engine exhaust into a hollow wing, with holes in the wing top for controlled issuance of the smoke.

Fig. 2 is a plan view, partly broken away, of a machine having a key board and electrical means for controlling the issuance of smoke from an airplane wing.

Fig. 3 is a bottom plan view of Fig. 2.

Fig. 4 is a vertical longitudinal sectional view of the machine, parts being shown in 65 elevation.

Figs. 5 and 5a are respectively partial top plan views of a complete wing provided with rows of orifices.

Fig. 6 is an enlarged sectional detail view 70 of an electrically actuated valve for controlling a wing orifice.

Fig. 7 is a top plan view of Fig. 6.

Fig. 8 is a section on the line 8—8 of Fig. 2.

Fig. 9 is a section on the line 9—9 of Fig. 8.

Fig. 10 is a perspective view of one of the keys.

Fig. 11 is a section on the line 11—11 of Fig. 4; and

Fig. 12 is a diagrammatic lay-out of the 80 electrical circuits employed in the apparatus.

While my invention in sky writing is not limited to the employment of an airplane for its performance, I have elected, by way of example, to describe and illustrate the operative means as applied to and operative with an airplane.

Thus, in Fig. 1 there appears an airplane having a fuselage A, supporting wing B, and exhaust pipe C, that leads from the engine (not shown).

The wing is shown as provided in its upper surface with a number of parallel rows of orifices 1 (see also Figs. 5, 5a). If the wing be composed of sheet metallic material the 95 engine exhaust may be admitted into the wing and will supply pressure that causes the smoke to issue in jets from the orifices, and if some oily or other suitable substance, be introduced into the exhaust to combine 100

therewith, obviously the issuing jets can be efficiently employed in sky writing.

I have shown a conduit 2 as communicating at one end with the wing interior, and with its other end having a flared entrance 3 that may be opposed to the rearwardly directed exit of exhaust pipe C, whilst also, being forwardly directed, receiving atmospheric pressure, in flight of the airplane, to thereby communicate pressure to the wing interior for expulsion of smoke from the orifices.

Each of the orifices 1 is equipped with a normally closed electrically operated controlling valve 4, which valves will be described hereinafter.

An operating machine 5, provided with a key board, keys and electrical connections, appears diagrammatically in Fig. 1, which figure also shows a generator of electrical current 6 as operated by a propeller 7, for creating during flight the energy required to actuate the valves and other working parts of the apparatus.

25 The orifices 1 it will be noted are in rows that extend spanwise of the wing, and also in rows that extend chordwise, and it is by the selective actuation of predetermined groups of the valves controlling their groups 30 of orifices that the shapes or forms of letters, characters and the like in smoke are permitted to issue from the groups.

The keys of the keyboard, each bearing 35 the designation of a letter or character to be produced by smoke jets are each adapted, when depressed, as by finger action, to connect a predetermined arbitrary group of orifices controlling valves with the negative pole of the source of electrical energy, the 40 depression of said key at the same time causing a motor to be energized, whereupon the rotor of said motor causes a switch lever to successively engage contacts that have leads which respectively connect with the positive 45 pole of the source of energy through all of the orifice controlling valves, whereby the circuits are closed in succession with respect only to the valves in the group that control the orifices required to issue smoke for forming the smoke letter or character represented 50 by the key that has been depressed.

For a more particular comprehension of the apparatus employed in the operation of the system reference is to be had to Fig. 4 55 which shows the complete machine 5 in vertical section.

Thus let 8 indicate the key board, which is provided with letter or character keys 9, each key having a stem 10 which, below the key board, carries the oppositely disposed contact blades 11, adapted to engage between the split contact members 12, 13, mounted on the insulation base board 14, to connect them electrically, thereby providing an electrical 65 path, of negative sign, through a conduct-

ing member 15, to a predetermined group of valves.

Lying beneath the base board 14 are a number of parallel levers 16, all pivoted on a transverse shaft 17 that is secured to the opposite side walls of the machine, said levers being held normally against the under surface of base board 14, by means of springs 18 that are anchored as to a lower transverse rod 19, and engage the rear ends of the levers. The key stems 10, at their lower ends are bifurcated, as at 20, enabling them to straddle and engage the levers 16 so that the depression of a key causes a lever engaged thereby to be depressed therewith.

Relatively short levers 21, disposed at opposite sides of the machine, are also pivoted at their rear ends on shaft 17, and at their front ends are connected by a transverse bar 22, that lies against the underside of levers 16, under the tension of springs 23, which are anchored to the side walls of the machine, as at 24, in a plane above said levers. Hence, the depression of any one of the levers 16 serves to similarly depress the levers 21, whose operation, as will presently appear, is intended to actuate certain moving parts of the apparatus for the purpose of releasing the motor and causing the circuits to be closed for operation of the orifice controlling valves.

Mounted in the side walls of the machine is a shaft 26 which carries bell-cranks, each having the arms 27, 28, each arm 27 carrying a link that connects the bell-crank with a lever 21. The link aforesaid may be adjustable in length, for which purpose it is composed of a threaded rod 30 which engages end pieces 31, 32. The end piece 31 has a yoke-like portion that is pivoted to the bell-crank arm 27, and the end piece 32 has a yoke-like portion whereby it straddles and pivotally engages a lever 21, at 29.

Secured to the shaft 26 intermediate its length is a socket piece 33, into whose socket 34 is entered the stem 35 of a pawl 36, a spring 37 in the socket serving to yieldingly hold the pawl extended. The arm 28 of one of the bell-cranks carries a contact shoe 38 that has sliding contact over fixed terminals 39, 40 that are secured, in spaced relation upon an insulation plate 25 that is mounted on a side wall of the machine, said shoe being adapted to bridge said terminals and thereby close an electrical circuit.

The terminals 39 and 40 are normally held unbridged to keep the circuit open, though adapted to be bridged by shoe 38 to close the circuit, thereby constituting a switch, the agencies whereby the switch is actuated including pawl 36, as will be described hereinafter.

Mounted upon the machine frame is a circular block 41 of insulation material, containing concentric rows of contact members

42 that extend through said block, the upper ends of members 42 lying flush with the upper surface of block 41, and their lower ends projecting below said block, where they 5 form binding posts to engage lead wires that extend to a set of binding posts 43 located, at the back of the machine, where they are readily accessible.

The contact members 42 bear consecutive 10 numbers that correspond with like numerals borne by the binding posts, for a purpose to be explained hereinafter, it being here stated, however, that lead wires connect contact members 42 and binding posts 43 bearing like numerals.

Secured to the block 41 and contained within the machine is a motor housing 44 that contains an electro-motor 45, whose rotor shaft 46 extends revolvably through block 41, 20 and carries, between the motor housing 44 and block 41, an eccentric disk 46a. Said disk 46a has a shoulder 47 which is normally engaged by a latch 48, that is slidable in a fixed guide 49, and has a stem 50, slidable in 25 a fixed guide 51, said stem adjustably engaging an elbow piece 52 which carries a pendent roller 53 that is normally located in the path of the pawl 36. A spring 54 lies between the fixed guide 51 and a collar 55 upon stem 50, 30 to normally urge the latch 48 into the path of rotation of shoulder 47, to thereby hold the eccentric disk 46a against rotation.

It will be noted that in the operation of any key lever 16, and the consequent depression of shaft 22 and levers 21, the links 30 thereby swing the bell-cranks with their shaft 26, whereby the pawl 36, through its engagement with roller 53, shifts the latch 47 out of the path of the shoulder 48 on disk 40 46a, leaving said disk free to rotate.

At the same time the swinging motion accorded the bell-cranks causes the shoe 38 carried by a bell-crank arm 28 to shift into bridging contact with both terminals 39, 40, 45 thereby completing an electrical circuit which includes the generator and the electro-motor, so that the electro-motor becomes energized and causes the rotation of its rotor shaft and the disk 46a that is secured to said 50 shaft 46.

Also the shaft 46 has connected thereto a switch lever 54 which is composed of insulation material and is adapted to swing over the upper surface of block 41. Said lever 54 55 has a contact member 55 yieldingly socketed, in its under surface, in opposed, contacting relation with a contact ring 56 that is embedded in the upper surface of block 41, said ring 56 being electrically connected with the negative pole of the generator, through a binding post 43. Also the switch arm 54 has yieldingly socketed in its under surface, contact members 57, 58, which are respectively in opposed relation with the concentric circles in the block 41 that contain the con-

tact members 42, whereby said switch lever, in its swinging movement, causes the contact members 57, 58 to make successive contact with all the contact members 42.

An electrical path, indicated at 59, connects the contacts 55 with contacts 57, 58. It must be understood that the purpose in rotating the switch lever, which occurs when any one of the finger keys is depressed, is to cause the operation of a predetermined group of valves controlling associated orifices in the airplane wing for the issuance of smoke in the form of the character represented by the key that is struck.

An example of the valves employed by me is shown in Fig. 6 and comprises a valve casting 60, having a seat 61 just below an orifice 1, said seat normally receiving a valve head 62, to close the orifice, as by the tension of a spring 63, and the valve stem 64 forming the core of an electro-magnet 65 that is included in the electrical circuit, whereby the valve is caused to open upon the closing of the switch. It will be noted that binding posts 66 carry the leads from the contact members 12, 13.

Variations within the spirit and scope of my invention are equally comprehended by the foregoing disclosure:

I claim:

1. Sky writing means comprising a smoke container provided with outwardly directed orifices, an electrically actuated valve for each orifice, to control it, means for introducing pressure into said container, a source of electrical energy, a key board having keys that each represent a character, circuit means that include all the valves, and selective means actuatable by individual keys for closing the circuit with respect to groups of valves whose orifices represent characters borne by respective keys.

2. The combination with an airplane of a hollow wing therefor provided with outwardly directed orifices, means for introducing the engine exhaust into said wing, an electrically operable valve for each orifice, to control it, an electric generator, a propellor to operate said generator, circuit means that include said generator and valves, a key board, character keys therefor, each bearing a different character, means intermediate the respective keys and different groups of said valves actuatable to close the circuit selectively for any group of valves whose orifices represent the character on a key, when said key is depressed to permit emission of exhaust only from that group of orifices.

3. The combination with an airplane having a hollow wing provided with outwardly directed orifices, means for introducing the engine exhaust into the wing, a valve for each orifice, selective means for operating the valves and means intermediate the selective means and the different groups of valves ac-

tunable to operate any group of orifices to permit the emission of exhaust only from that group of orifices.

4. The combination with an airplane having a hollow wing provided with outwardly directed orifices, means for introducing the engine exhaust into the wing, said means being open to the atmosphere to create pressure for the passage of the exhaust gases to said wing during the flight of the airplane, a valve for each orifice, selective means for operating the valves and means intermediate the selective means and the different groups of valves actuatable to operate any group of orifices to permit the emission of exhaust only from that group of orifices.

New York, N. Y., August 1st, 1930.

JOHN POPOFF.
